GEORGE E. HOYLE, OF LEOMINSTER, MASSACHUSETTS, ASSIGNOR OF ONE-HALF TO ALBERT L. CROWELL, OF BOSTON, MASSACHUSETTS, AND RAYMOND S. CASE, OF UNIONVILLE, CONNECTICUT.

COMPRESSED REED FOR WEAVING, &c.

SPECIFICATION forming part of Letters Patent No. 769,383, dated September 6, 1904.

Original application filed May 29, 1903, Serial No. 159,274. Divided and this application filed January 16, 1904. Serial No. 189,278. (No model.)

To all whom it may concern:

Be it known that I, GEORGE E. HOYLE, a citizen of the United States, and a resident of Leominster, in the county of Worcester and 5 State of Massachusetts, have invented a certain new and useful Compressed Reed for Weaving and Braiding, of which the following is a specification.

The invention relates to a compact or compressed reed formed from a fibrous material and adapted to be used in weaving, plaiting, or braiding to take the place of wooden reeds and ratan heretofore used in the several arts of manufacture.

15 This application is a division of an original application filed May 29, 1903, Serial No. 159,274.

The object of the invention is to produce as an article of manufacture a reed which is 20 a perfect substitute and, in fact, may be used to better advantage and with greater saving than the ordinary ratan and wooden reed is used.

A further object is to produce a manufactured reed which when formed into shape 25 will have great strength equal to the ordinary wooden reed in common use and the added advantage of much more resiliency.

A still further object is to produce a reed 30 by pressing a fibrous material into proper shape and of indefinite lengths in counter-distinction to the comparatively short lengths of ordinary wooden reeds.

The particular object in the present application is to produce a round reed of the class 35 described—that is, a reed having a uniform gage of round cross-section—made in indefinite lengths.

It is also the object to produce such a reed 40 without disturbing or distorting the lay of the fibers of the material, as is the case in twisted reed or twine-like material which is produced by twisting strips of paper or like material and compressing it or causing it to 45 maintain its form by the use of adhesives.

Referring to the drawings, Figure 1 illus-

trates a bobbin filled with the manufactured reed. Fig. 2 illustrates the reed on enlarged scale. Fig. 3 illustrates the reed woven or braided to form a finish or border. Fig. 4 59 illustrates the reed woven into a fabric.

It has long been common practice in the arts and manufacture to weave, plait, or braid strips of ratan and reed to form baby-carriages, baskets, chair-bottoms, and many 55 other articles; and the present invention has for its object the producing of a material from a fibrous material which will take the place in many instances of said ratan or reed and to secure such a material as will embody the 60 many advantages inherent in ratan or reeds, but which will be much more pliable and may be made in any length desired.

The ordinary ratan or reed cannot be secured in lengths beyond given limits, and it 65 is thus necessary to form many overlaps and joints in weaving or braiding any structure, which not only weaken said structures, but are unsightly in appearance. In the use of the reed herein described and claimed any 70 length desired may be secured. For instance, several hundred feet may be wound upon a bobbin and fed continuously through a suitable weaving or braiding machine to produce a finished structure of the woven material 75 practically free from joints and breaks and one which will take any desired finish even more readily than the regular ratan.

In using a compressed strip or reed formed of fibrous material there are particular advantages. It is very resilient and when bent or wound to form plaiting or interlaced with other materials there is little or no tendency for it to crack out. It forms an extremely strong article which will stand much abuse, and 85 even sharp blows will not cause fractures in the material, as they will if the ratan or wooden reed is struck a sharp blow. This extreme strength and pliability is due in great measure to the formation of the compressed reeds, 90 which being formed of fibrous material compressed into proper form without twisting or

distorting the fibers produces a reed which has little or no tendency to crack open or break in use. Furthermore, these compressed reeds will take a very high degree of finish, for the finishing material permeates the fibers and takes a firm hold thereon. The compressed reeds herein described are formed from a fibrous material composed of any desired ingredients which will form a suitable plastic pulp that may be formed into the required thickness and which being subjected to heavy pressures is compressed into a homogeneous mass. In practice these round reeds of compressed material may be formed by first building up a sheet or web of substantially square cross-section and then reducing said strips by compressing them into a round form, or they may be formed in flat strips of substantially square or rectangular cross-section and skived or cut as to the edges to give the required round form; but in either case the material is first formed into a pulp-like mass and subsequently compressed into the reeds.

25 A particular advantage in the use of this compressed reed resides not only in the better-finished product, but in the great saving of waste. In the use of ordinary ratan or reeds, which at the start are expensive, there is a great amount of waste owing to the fixed lengths of such material. In the reed herein described there need be no waste at all, inasmuch as the strips of reed may be made in any desired length and may be woven or braided by hand or machine and cut off without a waste of material.

In using ordinary ratan for purposes of manufacture in baskets, carriages, and like articles it must be bleached and put through processes to secure the desired effects of finish, which to a great extent impoverish the strength of the material and, in fact, often make it extremely brittle in addition to adding greatly to the expense of manufacture. In the compressed reed herein described the action of bleaches and finishing materials does not have the same deleterious effects. First of all it is not necessary to bleach the compressed strips, as they may be given any desired color while in plastic form and are ready for use without further treatment when used in machine or hand weaving or braiding. The compressed strips may be made absolutely uniform, which is a further advantage,

as ratan often varies with each different length used.

The terms "fibrous pulp" and "plastic" material are used throughout the specification and appear in the claims, as well as the term "compressed reed." These terms indicate the nature of the article of manufacture and are used to differentiate it from such materials as are commonly made in twine-like form. These latter are commonly formed by twisting up paper or like substances, often in conjunction with an adhesive, and may or may not be compressed into various cross-sectional forms. In any event material so formed has its fiber distorted, warped, or twisted, while in the article herein described and claimed the fiber is laid in a natural manner, as by precipitation or gravitation, and is then reduced, producing reeds in which the fiber is undisturbed as to its natural lay and is never warped or twisted. The structure is complete, and there is nothing about it which can untwist or separate to cause deterioration. It is a composite structure formed of fiber reduced to a homogeneous, hard, though resili- 75 ent material.

80 What I claim as my invention, and desire to secure by Letters Patent, is—

1. As an article of manufacture, a compressed reed formed from a fibrous pulp material, and having a circular cross-section. 85
2. As an article of manufacture, a compressed reed formed from a fibrous, plastic material, and having a circular cross-section. 90
3. As an article of manufacture, a compressed reed formed from a fibrous material reduced to a homogeneous, hard, resilient body, with the fibers in natural position, and having a circular cross-section. 95
4. As an article of manufacture, a compressed reed formed from a fibrous material, said material condensed and hardened into a reed with the fiber untwisted and non-distorted, and having a circular cross-section. 100
5. As a new article of manufacture, a compressed reed formed from laminæ of fibrous material reduced and hardened into a reed without distorting the natural lay of the fiber, and having a circular cross-section.

GEORGE E. HOYLE.
